SANITARY TOILET SEAT

Romaine Livingston Sullivan, Radnor, Pa., assignor, by mesne assignments, to Steriliseat Corporation, New York, N. Y., a corporation of New York

Application June 29, 1939, Serial No. 281,961

3 Claims.

(Cl. 4—233)

This invention relates to toilet seats and, more particularly, to an arrangement permitting the toilet seat to be maintained in a sanitary condition and to be thoroughly disinfected after each usage, and is in part a continuation of my prior application Serial No. 241,232, filed November 18, 1938, for Sanitary toilet seat.

Another object of the invention is the production in a device of this character of an arrangement such that the disinfection is carried out in a way leaving the seat in immediately usable condition.

A further and more specific object of the invention is the provision of a means for disinfecting the toilet seat by use of a non-heating sterilizing lamp.

Another object of the invention is to provide a structure of the character just noted in which means are provided to avoid shock to the sterilizing lamp.

These and other objects I attain by the construction shown in the accompanying drawings wherein, for the purpose of illustration, I have shown a preferred embodiment of my invention, and wherein:

Fig. 1 is a front elevation of a toilet seat constructed in accordance with my invention;

Fig. 2 is a section on line 2—2 of Fig. 1;

Fig. 3 is a front elevation showing a slightly modified form of my invention, the construction lines indicating the toilet bowl;

Fig. 4 is a section on line 4—4 of Fig. 3;

Fig. 5 is a section on line 5—5 of Fig. 3;

Fig. 6 is an enlarged section on line 6—6 of Fig. 3; and

Fig. 7 is an enlarged section on line 7—7 of Fig. 3.

Referring now more particularly to the drawings, the numeral 10 generally designates a closet bowl at the rear of which I provide a cabinet 11, the interior surface of which is formed as a reflector. The seat 12 illustrated is of the horse-shoe type and is normally maintained in elevated position through a spring 13, although, obviously, any other suitable means may be provided for this purpose. The cabinet 11 has an aperture 14 shaped to receive the seat, a baffle 15 defining the seat opening and being disposed, in the elevated position of the seat, slightly outwardly of the lower seat surface, as more clearly shown in Figure 2. This baffle may be supported in any suitable manner, being at present shown as comprising an integral extension of the upper wall of the cabinet and as braced to the rear wall of the cabinet by posts 16 which are secured

to both the baffle and rear wall. Within the cabinet, rearwardly of the seat, I mount sockets 17 for the reception of a non-heating sterilizing lamp 18, any suitable high-frequency ray lamp being employed for this purpose.

Below what is the lower end of the seat when in its raised position, I dispose a switch 19 controlling the lamp circuit, and it will be obvious that this switch will be closed each time that the seat is moved to its elevated position, with the result that the seat surface will be bathed in the disinfecting rays to thoroughly sterilize the same. The lamp selected should be of a type such that no appreciable heat is generated so that the seat may be comfortable in use. The seat may be equipped with the usual bowl-engaging bumpers 20 and with a handle, or handles, 21 whereby it may be moved to its lowered position, these handles being so disposed that they will not engage the bowl.

In Figures 3 to 7 I have illustrated a slightly modified form of my invention. In these figures the cabinet 11a includes an outer frame structure and an inner reflector element 11b, the latter being constructed of material which is especially adapted to the reflection of ultra violet rays and rays of the closely associated bands.

The reflector 11b, as noted, is shaped to deflect rays from the lamp 18 in such fashion that all portions of the seat will receive the benefit thereof, either by direct or radiated contact. The upper end of the cabinet 11a is constructed as a chamber 22 containing a transformer 23 and the actual switch 19a controlling lamp 18. The seat 12a is formed in two wings which are connected to a shaft 24 journaled in bushings 25 mounted in the walls of the cabinet 11a. Each wing is secured to the shaft through a hinge clip 26 rigidly secured both to the seat wing and shaft. The inner ends of these clips are abutted by bushings 25 and the outer ends of the shaft mount counterweights 27 which are likewise secured to the shaft and which abut the bushings 25.

In this manner, the wings of the seat can be so secured that they will accurately align with the openings defined by the cabinet walls and by a central panel 15a which, in the present instance, extends to the lower end of the cabinet and forms a closure for the chamber 22 in addition to affording a means for accurately defining the upper ends of the leaves 12a when in their elevated position. Through the bushing 25 counterweights 27 and hinge elements 26, which are connected by a sleeve 28 surrounding the

shaft, any possible displacement of the wings of seat 12a is prevented and it is possible to so dispose these wings that in their elevated position they will almost entirely close the opening 29 of cabinet 11a.

It will be obvious that, in order to insure proper closure, movement of the seat must be checked at a given point, and to this end one of the hinge elements 28 has secured thereto a bracket 30 having an adjusting screw 31 projected therethrough, which screw is adapted, as shown, to engage against the bottom wall 11c of cabinet 11a and so operate to check movement of the seat under influence of counterweights 21. It must, likewise, be obvious that movement of the seat under influence of either the spring or counterweight will be an accelerated motion, since the seat in its upward movement will have an effective loss in weight assisting such acceleration beyond the point to which it would be normally accelerated after once overcoming the inertia of initial movement. Lamps of the character suitable for this purpose are susceptible to shock, and this condition is accentuated in a device of this character due to the elongation of the lamp employed. For this reason, I provide a dash-pot mechanism-comprising a cylinder 32 which I pivot at 33 to a cup-shaped housing 34 secured to the rear wall of the cabinet. This dash-pot has arranged therein the usual piston 35 the stem of which, indicated at 36, is connected with a short arm 37 preferably secured to the second hinge element 28 in such fashion that as the seat 12a is drawn downwardly air is admitted to the cylinder and as the seat moves upwardly it is gradually expelled at a rate controlled by an adjusting device 38 which may be of any usual or preferred construction. For example, this device may be a screw loosely fitted in a threaded opening and a spring 39 utilized to regulate its engagement with the threads of the opening and, accordingly, the pressure at which air will escape about the screw through the threads.

In the present construction the switch 19a is of the tilting mercury tube type and is located in the upper end of the cabinet and operated through a pivoted lever 40 one end of which is engaged by the seat through an adjustable screw 41 at present shown as carried by sleeve 28 and the other end of which operates a vertically-extending rod 42 the upper end of which controls operation of switch 19a.

Since the constructions illustrated are, obviously, capable of considerable modification, I do not wish to be understood as limiting myself thereto except as hereinafter claimed.

I claim:

1. In a toilet, a bowl, a toilet seat movable to usable and unusable positions with relation to the bowl, a cabinet receiving the seat when in unusable position and closely fitting about the edges thereof without contacting the same, a lamp in said cabinet emitting a non-heating sterilizing ray, a reflector in said cabinet and directing the rays of the lamp to all portions of the upper surface of the seat, a normally open switch controlling the circuit of the lamp and closed by movement of the seat to unusable position, and means constantly urging the seat to unusable position.

2. In a toilet, a bowl, a toilet seat movable to usable and unusable positions with relation to the bowl, a cabinet receiving the seat when in unusable position and closely fitting without contact about the edges thereof, a lamp in said cabinet emitting a non-heating sterilizing ray and operative when the seat is in unusable position, a reflector in said cabinet and directing the rays of the lamp to all portions of the upper surface of the seat, means constantly urging the seat to unusable position, means to check movement of the seat at a predetermined position, a shaft rotatably supported by the cabinet and to which the seat is secured, an arm on said shaft and a dash-pot connected between said arm and the cabinet.

3. A toilet, a bowl, a toilet seat movable to usable and unusable positions with relation to the bowl, a cabinet receiving the seat when in unusable position and closely fitting without contact about the edges thereof, a lamp in said cabinet emitting a non-heating sterilizing ray, a normally open switch controlling the circuit of the lamp and closed by movement of the seat to unusable position, a reflector in said cabinet and directing the rays of the lamp to all portions of the upper surface of the seat, means constantly urging the seat to unusable position, a shaft rotatably supported by the cabinet and to which the seat is secured, an arm on said shaft and a dash-pot connected between said arm and the cabinet.

ROMAINE LIVINGSTON SULLIVAN.
